US00D517613S

(12) United States Design Patent (10) Patent No.: US D517,613 S
Shigeta (45) Date of Patent: * Mar. 21, 2006

(54) PLAYING CARD

(75) Inventor: Minoru Shigeta, Osaka (JP)

(73) Assignee: Angel Co., Ltd., Osaka (JP)

() Term: 14 Years

(21) Appl. No.: 29/192,613

(22) Filed: Oct. 27, 2003

(30) Foreign Application Priority Data

May 9, 2003 (CN) 03 3 10512

(51) LOC (8) Cl. 21-01

(52) U.S. Cl. D21/376

(58) Field of Classification Search D21/376-384;
D6/582; 273/292-293

See application file for complete search history.
